UNITED STATES PATENT OFFICE.

GARRISON BABCOCK, OF EVERETT, WASHINGTON.

TELECHRONOMETER CURRENT CONVERTER.

Application filed October 15, 1921. Serial No. 508,038.

My invention relates to means for converting, or securing reversals of, current flow, in electrical circuits and is concerned particularly with an improved converter, for 5 securing current reversals in a telephone system employing a reversal responsive metering device and for applying them thereto, especially that type of reversal responsive metering device, known under the trade- 10 name of "telechronometer".

While my present invention is particularly adapted for use in telephone systems, in which the service to the subscriber is metered through the application of current reversals 15 to the meter, it is not limited to employment in telephone systems, or if employed in a telephone system, it is not limited to the specific telephone system, nor to the specific method of connection and application 20 which I have described in the following specification.

My present invention which is along the line of the invention set out in my co-pending application, Serial No. 476,713, filed 25 June 11, 1921, aims primarily to provide a simple, positive and inexpensive means for securing reversals of current flow suitable for actuating telechronometers on telephone lines and the like. Like my co-pending application, my present invention provides a 30 resistance, or pair of resistances, for each direction of current flow so connected that by reducing a resistance or pair of resistances, the potential to the meter will be reversed 35 quickly but without producing any abrupt change in current flow on the telephone system. My present invention provides an improved arrangement for alternately compressing and releasing the resistances to 40 shift the flow of current quickly and smoothly from one direction of flow to another; a balance indicator system having means for accurately and reliably indicating to the attendant any out of balanced condition in the 45 resistances and a simple adjusting arrangement for quickly and positively adjusting the resistances to a balance. Where a pair of resistances are employed for each direction of current flow, this adjusting arrangement 50 includes means for adjusting the sets of resistances relative one another, and means for adjusting either resistance of either set relative the other. To assist in the proper adjustment of the various resistances, my 55 present invention still further provides

means whereby the attendant may readily apprise himself of the performance, operation, or value of any of the individual resistances employed.

Certain constructural features and arrangements of my present invention are 60 novel and important, and these together with such other provisions as have not been hereinbefore set forth will appear from the following detailed description taken with an 65 inspection of the accompanying drawings in which:

Figure 1 is a diagrammatic layout of a telephone system embodying my present invention;

Figure 2 is a front elevational view partly diagrammatic of the rheostats and arrangement for operating the same; and

Figure 3 is a detached and simplified diagram of the pole changer circuit showing the 75 arrangement for indicating any out of balanced condition in the resistances.

As illustrated in Figure 1, the system in connection with which I have illustrated a particular embodiment of my present invention, comprises the calling station A, called station B, and a connecting circuit C, located at a central switchboard.

At the subscriber's station A and B, I have illustrated in conjunction with the usual 85 telephone apparatus, call registering devices 1 and 1' respectively adapted to be operated by reversals of current. The particular meter or call registering device illustrated is described in my co-pending application, 90 Serial No. 508,037 filed Oct. 15, 1921. Any other suitable metering device operating upon reversals of current, such as for example the meter described in my co-pending application, Serial No. 476,713, filed June 11, 95 1921 may be employed, as my present application relates more particularly to the manner of and means for securing the reversals of current.

The meter described in my above referred 100 to applications are characterized by the use of two series coils connected in the two sides of the talking line, and provided with suitable polarizing means and counter-actuating mechanism, whereby a complete cycle of 105 the reversal of current is required for the actuation of the counting mechanism.

The calling station A comprises the usual transmitter 2, receiver 3, induction coil 4, hook switch 5, and ringer or call bell 6. 110

The station is connected to suitable terminals at central over the line wires 7 and 8, which line wires are provided with connections to a central battery 10, for supplying normal polarity of current over the line. The line is provided at central with a suitable answering jack 11, and multiple jacks, such as 12, connected through a suitable cut-off relay 13, in a manner well known in the art. The line to station A is provided with a suitable line signal 14, for signaling or indicating to the operator at the exchange that a connection is desired. The signal 14 is controlled or governed by a line relay 15.

15 The connecting cord circuit C with which the central operator is provided, includes an answering plug 16 and a ringing plug 17, for cooperation with the line and multiple jacks, in making connections and inter-connections. The answering plug 16 is connected to the talking strands 18 and 19, and is provided with a third conductor 20 for controlling the actuation of the cut-off relay 13, and the sleeve relay 21. A listening key 22 25 for placing the operator's set 24 in communication with strands 18 and 19 is also provided. At the ringing end of the cord circuit, plug 17 is connected to talking strands 25 and 26, and is also connected to a third 30 conductor 27, which serves to energize the line cut-off relay 13' of the called line 7', 8' and the sleeve relay 28. The operator is provided with a ringing key 29, which is adapted for connecting a ringing generator 35 30, or other source of ringing current to the conductors of the called line.

While I have illustrated a three-strand cord circuit in the particular embodiment of my present invention, which I have elected 40 to describe, it is to be understood that the invention is not limited in any manner to embodiment in a three-strand cord circuit and that my illustration of the same, as in the case of my co-pending application referred to hereinbefore, is for the purpose of clearly showing the invention in as simple a manner as possible.

One end of cord circuit C is supplied with battery from the central source 10 over suitable connections which will be described later. These connections include the answering supervisory relay 31, which, in connection with sleeve relay 21, controls the supervisory signal 32. In a similar manner, battery is fed to the ringing end of the cord circuit from the central source 10 over suitable connections, in this case wire 33, winding 34 and conductor 35 to the tip strand 25, and from the other side of the battery, over 50 wire 36, winding 37 of the supervisory relay 38, conductor 39, to the ring or sleeve strand 26 of the ringing end of the cord circuit. The potential upon the ringing end of the cord circuit always remains in the same direction, due to the connections above de-

scribed, so that no reversals of current upon the called line occurs, the calling line only being charged for the call.

The pole changer device or current converter comprises two pairs of compression resistances R^1 , R^2 and R^3 , R^4 between which battery is connected over the conductors 45 and 46. The terminals 47 and 48 of the pole changer lead to the talking strands 18 and 19 respectively through the supervisory relay 31. The resistances shown are of the carbon pile type well known in the art. The resistances R^1 and R^2 are mechanically compressed together and the resistances R^3 and R^4 are actuated simultaneously by an arrangement which is one of the important aspects of my present invention, and will be described later.

One terminal of the battery 10 is connected with the lower ends of the resistances R^1 and R^3 by way of conductors 45, 50 and 45, 51 respectively. The upper end of the resistance R^1 is connected by way of a conductor 52 with terminal 48 of the pole changer. The upper end of the resistance R^3 is connected by way of conductors 53 and 54 with the terminal 47. The lower ends of the resistances R^2 and R^4 are connected to the opposite terminal of the battery 10 by way of suitable conductors 55 and 56 respectively. Obviously, if the resistances R^1 , R^2 and R^3 , R^4 are all equal there will be no difference of potential at the terminals 47 and 48. If the resistances R^1 , R^2 are simultaneously compressed to reduce the value of the same, the terminal 47 will exhibit a strong positive potential, while the terminal 48 will exhibit a strong negative potential. In other words, when the resistances R^1 , R^2 are simultaneously compressed, a current flow will be set 105 out through the talking strands as follows: from battery 10, through conductors 45 and 50, resistance R^1 and out through the line by way of the conductor 52 and the terminal 48, back from the line through terminal 47, conductor 54, resistance R^2 and to battery 10 by way of conductors 55 and 46.

If now, the pressure on resistances R^1 and R^2 is relaxed or released and simultaneously the pressure on resistances R^3 and R^4 is increased, the terminal 47 will exhibit a strong negative potential, while the terminal 48 will exhibit a strong positive potential. When the resistances R^3 and R^4 are simultaneously compressed, the current flow out through the talking stand is as follows: conductors 45, 51, resistance R^3 , conductors 53 and 54 out through the line by way of terminal 47, and back through conductors 52 and 58, resistance R^4 and conductors 56 and 46 to battery. The change from one potential to the other is performed without any interruption or abrupt change in current flow.

In order that the attendant may readily

observe any out-of-balance conditions in the rheostats and easily adjust the same to a balance, I have incorporated a balance indicator 60 between the line feed and the battery.

- 5 It will now be apparent that when resistances R^1 , R^2 are simultaneously compressed, a flow of current will be set up from battery 10, conductor 62 through the coil 61 of the indicator 60, which is now in parallel with resistance R^1 , out through the line by way of conductor 63 and back from the line through the coil 64 of the indicator, which is now in parallel with resistance R^2 , to battery by way of the conductors 65 and 66.
- 10 When the resistances R^3 , R^4 are simultaneously compressed, a flow of the outgoing current will be set up through R^3 and the coil 64 back to battery while a flow will be set up through coil 61, resistance R^4 and back to battery. In this case the indicator coil 61 is connected in a local circuit in series with R^3 and the indicator coil 64 is connected in series with resistance R^4 . In the first instance, the voltage impressed upon the coil 61 is dependent upon the I R drop across R^1 , and the flow through the coil 64 is similarly dependent upon the I R drop across resistance R^2 . In the second instance, the flow through the coils 61 and 64 will be dependent upon the respective values of the resistances R^3 and R^4 , which are connected in series with said coils 61 and 64, respectively. In either case, any out-of-balance condition will be indicated so that it may be corrected in a manner which will herein-after appear.
- 15
- 20
- 25
- 30
- 35

In order to clarify the operation of the pole changer, I have shown in Figure 3 a detached and simplified diagram of the

- 40 connections showing the relation of the resistances in the circuits. The battery 10 is connected to the common terminal 68 of the resistances R^1 , R^3 and the common terminal 69 of the resistances R^2 , R^4 . When the resistances R^1 , R^2 are compressed and pressure on resistances R^3 , R^4 relaxed current flows out through resistances R^2 by way of terminal 47 over the line and back by way of terminal 48 and through resistance R^1 to battery. When the resistances R^3 , R^4 are compressed and pressure on resistances R^1 , R^2 relaxed current flows out through resistance R^4 by way of terminal 48 over the lines and back by way of terminal 47 and through resistance R^3 to battery 10. When the supply is by way of the resistances R^1 , R^2 , there will be a flow set up through the coils 61 and 64 in the directions indicated by the arrows *a* and *b* respectively, while when the supply is by way of the resistances R^3 , R^4 , the current flow set up in coils 61 and 64 will be in the same direction. Suitable pointers 72 indicate the respective flows through the coils 61 and 64 and thereby the respective values of the
- 45
- 50
- 55
- 60
- 65

two resistances or rheostats, through which the flow to and from the line is taking place.

The arrangement for actuating or compressing the pairs of resistances, which arrangement forms another important aspect 70 of my present invention, comprises a pressure cylinder 73 for the rheostats R^1 , R^2 and a pressure cylinder 74 for the rheostats R^3 , R^4 . Piston rods 75 and 76 connected at their inner ends to suitable pistons within 75 the cylinders 73 and 74 respectively are adjustably connected at 77 and 78 with rheostat actuating shoes 79 and 80. Actuation of the respective rheostats is had by engagement of these actuating shoes with the insulated buttons 81 thereof. The supply of compressed air or other suitable motive fluid from the common intake conduit 82 to the cylinders 73 and 74 is regulated by suitable adjustable pressure regulators or 80 pressure reducing valves 83 and 84. The conduit 82 may communicate with any suitable source of pressure. Conduits 86 and 87 provide exhaust outlets for discharging or exhausting the pressure from the chambers 73 and 74, while suitable valve members 88 and 89 control the flow to an exhaust from the respective pressure chambers. The pressure chambers 73 and 74 are provided with suitable pressure gauges 90 95 and 91 respectively.

The blocks 77 and 78 through which the rods 75 and 76 are connected to the actuating shoes 79 and 80 are adjustable along the respective shoes so that any out of balance condition in the rheostats may be quickly and conveniently adjusted, by moving the block along the actuated shoe to the desired position. It will now be apparent that the actuation of one pair of resistances or rheostats relative the other pair may be varied to suit the particular conditions in question by regulating the pressure admitted to the chambers 73 and 74 by means of the pressure regulators 83 and 84, while the degree 100 of actuation of any resistance, relative the other resistance of the same set may be quickly and conveniently adjusted through the connections 77 and 78.

The actuating arms 92 and 93 for controlling the valves 88 and 89 respectively are connected at their free ends to the opposite ends of a link 94, which link 94 is connected by a pin joint at its center to the upper end of actuating lever 95. A pair 115 of bridging contact fingers 96 and 97 carried by the opposite end of the bar 95 are adapted for bridging terminals 98, 99 and 100, 101 of a valve controlling circuit. The lever 95 is pivotally mounted centrally and is rigidly joined to a cross bar 102. The cross bar 102 is connected at its opposite ends through suitable links 103, 104 with the plungers or cores 105, 106 of a pair of solenoid windings 107, 108. The terminals 120 125 130

99 and 101 are grounded at 109 (Fig. 1). The circuits through the solenoid windings 107 and 108 are controlled by a pair of time controlled relays 110 and 111. The windings of the relays 110 and 111 are connected at one end to a battery 112 or other suitable source, which source is grounded as shown at 113. The circuits through the relays 110 and 111 are governed by a time controlled circuit controller, which includes a cam wheel 117 mounted for example on the second shaft of a standard clock and contacts 114 and 115 which are alternately closed by engagement of the cam portions 15 of the wheel 117 therewith. These contact pins 114 and 115 are arranged at substantially 90° from each other and the cam or wheel has two projections 180° apart so that the polarity is shifted every fifteen seconds. 20 Energization of the relay 110 actuates armature 116 to close the contacts 118 and thereby complete the circuit from battery 112 to solenoid winding 107 to ground 109 by way of the terminals 98 and 99 and finger 96, assuming the contact finger 96 is in engagement with the terminals 98 and 99. 25 Energization of the winding 107 causes movement of the plunger 105 inwardly, thereby swinging the bar 95 about its pivot 30 to admit pressure to one of the cylinders for example 73, and exhaust the other 74, and thereby compress the resistances R^1 , R^2 and release the pressure upon other pair R^3 , R^4 . This movement of the bar 95 moves the 35 contact 96 out of engagement with the contacts 98 and 99 and the contact 97 into engagement with the contact pieces 100, and 101 selecting the circuit through the winding 108 which circuit is closed at the contacts 40 120 by engagement of the cam wheel 117 with the contacts 115. Completion of the circuit through the winding 108 swings the bar 95 in the opposite direction to compress the other pair of resistances R^3 , R^4 and selects the circuit through the winding 107. 45 In this manner, a change from one direction of current flow to the other is periodically effected in the calling line without any interruption or abrupt change. 50 To assist in the proper adjustment of the various resistances or rheostats, I provide an arrangement for indicating to the attendant the performance or operation of any of the individual rheostats. This includes a 55 suitable voltmeter 125, a selecting switch 126 for connecting either of the resistances R^1 , R^2 , R^3 or R^4 individually thereacross and the necessary circuit connections therebetween. 60 I shall now describe briefly the operation of the particular system illustrated. Assuming that subscriber A desires to be connected to subscriber B, the receiver 3 is raised, thereby completing a circuit from 65 battery 10 as follows:

Battery 10, conductors 62, 130 and 131, line relay 15, line wire 8, through the instruments and meter at the station and back through line wire 7, conductors 132, 133, 66, and 46 to battery 10. Since the meter requires a complete cycle of current reversed it is not now actuated. Line relay 15 being thus energized closes a circuit from battery through line signal 14, indicating to the operator at the exchange that a connection is desired. The operator thereupon makes connection with the answering plug 16, effacing the line signal and connecting the strands 18 and 19 to the line wires 7 and 8. Current of the prevailing polarity thereupon flows out over the talking strands 18 and 19, and over the line wires 7 and 8 and supplies current to the instruments at the sub-station A. The operator through the medium of the listening key 22 communicates with the subscriber and receives the order for the desired connection, and assuming that the subscriber B is desired selects and tests the terminals of said line and proceeds to make the connection. The ringing key 29 is actuated to project ringing current over the called line, and when the party B answers, current flows in normal direction over the line of the called party, and conversation between the parties may be carried on. 80 85 90 95 The operation of the pole changer continues at all times. In the particular system illustrated, the calling party is charged for all of the time consumed in making a connection and consummating the conversation. It is to be understood, however, that the charge may be for only the time during which the connection between the parties is established. This may be accomplished by cutting the terminals of the pole changer into the talking circuit of the calling line through the contacts of the supervisory answering relay 34 so that normal polarity of current prevails on the calling line until the called party responds. This is well known in the art and is, therefore, not illustrated here. 100 105 110 115 The operation of the pole changer is as follows: 120 The time controlled wheel 117 rotates continuously, successively closing the contacts 114 and 115 and thereby the circuits through the solenoid windings 107 and 108. The closing of these circuits is only momentary, sufficient to operate the valves 88 and 89 and set the connecting piece or bridge carried by the bar 95 for closing the other circuit. The operation of the valves 88 and 89 in turn controls release of one set of resistances and compression of the other set. A complete cycle of change of polarity occurring in the calling line from positive to negative and back to positive or vice versa causes an actuation or registration upon the 125 130

meter 1 at the calling station. If desired, the meter may be actuated by a reversal of current only i. e. from positive to negative or vice versa, but I prefer the use of a meter which requires a complete cycle of alternation for registration of a count, such as the type set out in my hereinbefore referred to co-pending application.

I do not intend to be limited to the particular embodiment shown and described.

The invention is not to be limited to telephone systems and the use of the compressible resistance in connection with the time controlled mechanism for operating the same is not to be limited to current reversal as mere variations in current strength may be employed in certain situations.

I claim:

1. In combination, a pair of carbon piles, fluid pressure means including a single pressure cylinder and a piston, and means having adjustable connection with the piston for compressing both said piles by means of said piston, the adjustable connection between said last means and the piston permitting adjustment of the compression of one pile relative the other by means of said piston.

2. In combination, a pair of carbon piles, means for compressing said piles, and means for adjusting the compression of one of said piles with respect to the other by said compression means.

3. In combination, a compressible resistance, fluid pressure means for compressing said resistance to vary the same, valve means for governing the action of said fluid pressure means, an electro-magnetic device, a circuit therefor, and means controlled by said electro-magnetic device for operating said

4. valve means and simultaneously interrupting said circuit independently of said fluid pressure means.

4. In combination, a variable resistance, means for varying said resistance, electro-magnetic means for operating said resistance varying means, and a circuit therefor, said resistance varying means being operated and said circuit interrupted automatically by the operation of said electro-magnetic means and independently of said resistance varying means.

5. In combination, a pair of variable resistances, a member for varying said resistances jointly, and an actuating member for said first member, said actuating member having adjustable connection with said first member to permit varying the relative joint variation of said resistances, said adjustable connection comprising a member pivoted to one of said first members and slidably adjustable upon the other of said members.

6. In combination, a pair of carbon piles, a shoe for compressing said carbon piles, a shoe actuating member, and an adjustable

connection between the shoe actuating member and said shoe, said means comprising a member pivoted to the actuating member and slidably adjustable upon the shoe.

7. In combination, a pair of variable resistances, a shoe for varying said resistances, a fluid pressure chamber, a piston operable in said chamber, and a mechanical connection between said piston and said shoe.

8. In combination, a pair of variable resistances, an actuating member for varying said resistances, a fluid pressure chamber, and a piston operable in said chamber, said piston having adjustable mechanical connection with the actuating member between said resistances.

9. In combination, two pairs of adjustable resistances, a member for varying the two resistances of one pair, a member for varying the two resistances of the other pair, fluid pressure means for actuating said members, valve means for adjusting the relative variations between the two pairs of resistances and mechanical means for adjusting the relative variations between the two resistances of each pair.

10. In combination, two pairs of adjustable resistances, a member for varying the two resistances of one pair, a member for varying the two resistances of the other pair, a pair of fluid pressure chambers, pistons operable one in each of said chambers and one having connection with each of said resistance varying members, a fluid supply conduit for said chambers, valved connections from said conduit to said chambers, means for automatically operating said valved connections alternately and separate controlling means for said connections.

11. In combination, a pair of resistances, a pair of fluid pressure devices for varying said resistances, and means for regulating said pressure devices to control the relative variations effected in said resistances thereby.

12. In combination, two pairs of carbon piles, a shoe for compressing one of said pairs of carbon piles, a shoe for compressing the other of said pairs of carbon piles, a pair of fluid pressure operated pistons, a shoe actuating member subject to the pressure of one of said pistons, said member having adjustable connection with one of said compressing shoes, a shoe actuating member subject to the pressure of the other of said pistons, said member having adjustable connection with the other of said compression shoes, and means for regulating the pressure on said pistons to vary the actuation of the compressing shoes by the shoe actuating members.

13. In combination, two pairs of resistances, a source of current, means for alternately causing a flow of current through said pairs of resistances, and a balance indicator having a uni-directional circuit in circuit

with both said pairs of resistances to indicate any out of balance condition in either of said pairs of resistances.

14. In combination, a Wheatstone bridge circuit having two pairs of resistances in its arms, a source of current connected across said bridge, and a balance indicator having a pair of coils connected in parallel with the resistances of one pair of said resistances, 10 and series connections between said indicator coils and the other pair of resistances.

15. In combination, a pair of resistances, a second pair of resistances, means for alternately causing a flow of current through 15 said two pairs of resistances, and a common balance indicator for indicating any out of balance in the resistances of both said pairs.

16. In combination, a potentiometer circuit, comprising two variable resistances, terminals connected to said potentiometer circuit, fluid pressure means for varying said resistances alternately, and time controlled means governing said fluid pressure means.

17. In a telephone system, a talking line, 25 means for supplying current periodically in reverse directions over said line, said means comprising a potentiometer circuit including a pair of non-interruptible variable resistances, a pair of fluid pressure operated pistons for alternately varying said resistances, a time controlled circuit controller for controlling said pistons and indicating means for determining the variation of said resistances.

18. In combination, a pole changer comprising a pair of non-interruptible variable rheostats, a pair of fluid pressure operated pistons for changing the resistances of said rheostats alternately, electro-magnetic means 40 for controlling said pistons and a time controlled circuit for said electro-magnetic means.

19. In a pole changer, a pair of non-interruptible rheostats, movable means for alternately varying the resistance of said rheostats, a pair of fluid pressure operated pistons, electro-magnetic means for controlling said pistons and time controlled means for controlling of said electro-magnetic means.

20. In combination, a pair of non-interruptible rheostats for changing the polarity of an electrical circuit, a voltmeter and means for connecting either of the rheostats 55 separately across said voltmeter to indicate the resistance of the respective rheostats.

21. In combination, a Wheatstone bridge circuit having compressible resistances connected in the arms thereof, said resistances 60 being mechanically grouped in two opposite pairs, fluid pressure operated means for compressing said pairs of resistances alternately and means for indicating a condition of electrical unbalance separately between the two 65 resistances of each pair.

22. In combination, a compressible resistance, a fluid operated piston, valve means governing the action of said piston, means for controlling said valve means, and time controlled means governing the action of 70 said valve controlling means.

23. In combination, a compressible resistance, a circuit having a device responsive to the compression of said resistance, a fluid operated piston, valve means governing the 75 actuation of said piston, means controlling said valve means, and time controlled means governing the action of said valve controlling means.

24. In combination, a compressible resistance, a circuit having a counting device responsive to compression of said resistance, a fluid operated piston for compressing said resistance, valve means governing the actuation of said piston, a magnet for actuating 80 said valve, a time controlled contact device governing the energization of said magnet.

25. In combination, a compression rheostat, a fluid operated piston, a cylinder, a fluid connection therefor, a pressure regulating valve governing the pressure applied to the piston, a valve for admitting and exhausting fluid pressure to and from the cylinder, means for controlling said last valve, and time controlled means governing 95 the action of said valve controlling means.

26. In combination, a compression rheostat, a fluid operated piston, a cylinder, a fluid connection therefor, a pressure regulating valve governing the pressure applied to the piston, a valve for admitting and exhausting fluid pressure to and from the cylinder, means for controlling said last valve, time controlled means governing the 100 action of said valve controlling means, and means for indicating the relative electrical 105 resistance of said rheostat.

27. In combination, a pair of compression rheostats, a common operating piston for compressing said rheostats, a cylinder therefor, an adjustable mechanical connection between said piston and said rheostats for distributing the pressure between said rheostats, and electrical indicating means for indicating the relative electrical resistances of 115 said rheostats.

28. In combination, a potentiometer circuit comprising two variable resistances, terminals connected to said potentiometer circuit, fluid pressure means for varying 120 said resistances alternately, and automatic means for governing the action of said fluid pressure means.

29. In a telephone system, a talking line, means for supplying talking current periodically in reverse directions over said line, said means comprising a potentiometer battery supply circuit including a pair of non-interruptible variable resistances, a pair of fluid pressure operated pistons for alter- 125 130

nately varying said resistances, an automatic circuit controller for controlling the application of pressure to said pistons, and indicating means for determining the variation of said resistances.

30. In combination, a pole changer comprising a pair of non-interruptible variable rheostats, a pair of fluid pressure operated pistons for changing the resistances of said rheostats alternately, and electro-magnetic means for automatically controlling the pistons to actuate said resistances periodically.

31. In a pole changer, a pair of noninterruptible rheostats, movable means for alternately varying the resistance of said rheo-

stats, a pair of fluid pressure operated pistons, electro-magnetic means for controlling said pistons, and a rotating shaft for controlling the electromagnetic means to actuate the rheostats periodically.

32. In combination, a compressible resistance, a fluid operated piston, valve means governing the action of said piston, a circuit having electromagnetic means for controlling the valve governing means, contacts for the circuit and a constantly moving cam for actuating said contacts.

In witness whereof, I hereunto subscribe my name this 6th day of October 1921.

GARRISON BABCOCK.
